Patented Dec. 12, 1922.

FIG. 5
C. E. Barkley
INVENTOR
By J. M. Bond
ATTORNEY

UNITED STATES PATENT OFFICE.

CHARLES ELIAS BARKLEY, OF FORT WILLIAM, ONTARIO, CANADA.

PLAY AND ORNAMENTAL BALL.

Application filed January 29, 1921. Serial No. 441,022.

To all whom it may concern:

Be it known that I, CHARLES E. BARKLEY, a citizen of the Dominion of Canada, residing at Fort William, in the District of 5 Thunder Bay and Province of Ontario, Canada, have invented certain new and useful Improvements in Play and Ornamental Balls, of which the following is a specification.

10 The present invention relates to playing ornamental or return balls and more particularly to that type—known in the trade, as the composition type of hand ball.

15 A further object is to provide a device of the character described, which is formed of some relatively light material such as wood pulp or ground paper and which when finished assumes the appearance of a snow ball.

20 With these and other objects in view, the invention consists in the construction, combination and arrangements of parts, as will be hereinafter fully described, illustrated in the accompanying drawings, and pointed 25 out in the claims hereunto appended.

Figure 1 is an elevational view of the improved ball.

Fig. 2 is a vertical axial section illustrating the preferred embodiment of the device.

30 Fig. 3 is a modified form of ball with the inner filler formed of wood.

Fig. 4 is a similar view with a wood filler, within the outer casing.

35 Fig. 5 is a further modification, illustrating the ball with a flaked paper and mica core, and

Fig. 6 is a fragmental section of the same with a cord attached thereto.

40 Referring to the drawings like numerals designate like parts in the various drawings.

In the construction of the improved ball a quantity of pulp, consisting of old newspapers, or building paper is moulded in solid 45 spherical form as in Figure 1. Then this spherical body is baked or sun dried to impart requisite hardness thereto. A covering 6 of suitable white material, such as white

paint is then imparted to the outer surface of the pulp core which causes the same to resemble a snow ball. 50

In the modification illustrated in Fig. 3, the ball is formed with a solid wooden core 7 around which is moulded a pulp-casing 8. When this pulp casing 8 has been hardened 55 a coat of white paint 9 is added to finish the ball to its particular degree of whiteness.

In the modification illustrated in Fig. 4, the ball is formed with a comminuted wooden core 10, around which is pressed a 60 pulp outer covering 11. This pulp outer covering 11 is then painted white or dipped into a suitable solution to transmit to the same the appearance of a snow ball.

In Fig. 5 the ball is formed with a core 65 12 of paper and mica flakes and an outer covering of paper pulp 13, suitably dried and being painted white as in the other forms described.

In Figs. 1 and 6 the balls are illustrated 70 attached to return strings 14 and 15, which extend through the pulp outer casings 16 and have their knotted ends 17 embedded with the material comprising the core 18. The balls may be formed of shredded cotton 75 fibre mixed with pulp and hardened having the white coating as in the other forms.

It is obvious, that the balls described, due to their light construction and weight and resultant of their white color, the same will 80 look like snow balls and be resilient. The cords may be secured to the inner cores of the balls during the moulding operation and thus the game of return ball may be played.

Likewise cotton batten may be attached by 85 a proper adhesive to the outer surface of the pulp covering.

From the foregoing it is thought that the construction of my invention will be clearly understood, and, therefore, a more extended 90 explanation has been omitted.

What I claim as new is:

1. As a new article of manufacture, the herein described ball comprising a core formed of a porous material moulded and 95 dried and an outer casing of paper pulp

2
enclosing the said core and painted white to represent a snow ball and a string having a knotted end embedded in said porous material.

5 2. As a new article of manufacture, a play ball formed with a paper and mica core, a pulp outer casing surrounding said core and said casing being covered with a

white substance to impart to the said ball the appearance of snow.

In testimony whereof I affix my signature in the presence of two witnesses.

CHARLES ELIAS BARKLEY.

Witnesses:

H. A. PHILLIPS,
E. R. BINGHAM.
